UNITED STATES PATENT OFFICE.

JOHN M. LOWE, OF BUTLER, INDIANA.

AUTOMOBILE-JACK.

1,249,437.

Specification of Letters Patent. Patented Dec. 11, 1917.

Application filed March 21, 1917. Serial No. 156,352.

To all whom it may concern:

Be it known that I, JOHN M. LOWE, a citizen of the United States, residing at Butler, in the county of Dekalb and State of Indiana, have invented a new and useful Automobile-Jack, of which the following is a specification.

The present invention appertains to jacks, and aims to provide a novel and improved device of that character adapted especially for jacking up automobiles which are encumbered at the front and rear by a bumper and tank, respectively, or the like, so that the axles are not readily accessible for the use of ordinary jacks.

It is the object of the invention to provide a jack which can be readily moved under an automobile, from either end, and which is operable in a convenient and effective manner for jacking up either axle.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention is illustrated in the accompanying drawings, wherein:—

Figure 1 is a plan view of a double jack embodying the present improvements.

Fig. 2 is a side elevation thereof.

Fig. 3 is an enlarged sectional detail on the line 3—3 of Fig. 1, illustrating one of the supporting casters.

Fig. 4 is a section on the line 4—4 of Fig. 3.

Fig. 5 is a fragmental plan view illustrating a modification of the structure shown in Fig. 1.

Fig. 6 is an elevation of one of the standards.

Fig. 7 is a similar view illustrating a modified form of standard.

Fig. 8 is a perspective view of a single jack embodying the improvements.

Fig. 9 is a sectional detail illustrating a means for adjustably supporting the lever.

The jack embodies a base 1 composed of side bars 2 connected at one end by a cross piece 3, and said bars converge toward their other ends, the latter ends being provided with the upturned portions or posts 4 pro-

vided at their upper ends with the horizontal brackets 5 projecting away from the cross piece 3.

The base or base frame is preferably rendered portable, in order that it can be readily moved about on the floor by itself or with the vehicle supported thereon. Thus, upper and lower plates 6 and 7 are secured to the corners of the base between the bars 2 and cross piece 3, and bearings 8 are bolted or otherwise secured upon the plates 6. The plates 7 have depending bearings 9 in which the upstanding caster spindles 10 are mounted for rotation. A head 11 is secured upon the upper end of each spindle 10 and anti-frictional bearing balls 12 are disposed between the head 11 and corresponding bearing 8. Anti-frictional rollers 13 are also preferably disposed between the spindles 10 and bearings 9 in order that the caster can rotate easily about a vertical axis. The lower end of the spindle 10 has an angularly extending bearing 14 through which a transverse axle 15 is journaled, a pair of wheels 16 being secured upon the terminals of said axle or being mounted for rotation upon said axle. One of these casters is disposed at each corner of the frame, and another caster is provided near the other end of the frame to provide a three point support for the base or frame. Thus, plates 6' and 7' are secured to the bars 2 near the posts 4, and a plate 8' is secured upon the plate 6' to serve the purpose of the bearings 8 above described.

A substantially horizontal lifting lever 17 is carried by the base or frame, and embodies a pair of side bars 18 converging from one end to the other, similar to the bars 2. Those ends of the bars 18 which are farthest apart are connected by a cross rod 19, and the bearings 8 have concaved seats 20 for the rod 19, to fulcrum the corresponding end of the lever 17 to the base. The other terminals of the bars 18 extend across the posts 4 at the outer sides thereof, and this end of the lever is raised and lowered by a windlass or winch as will be described presently.

The windlass for actuating the lever 17 embodies a short longitudinal shaft 21, providing a drum, and journaled in bearings 22 and 23 secured to and disposed between the brackets 5, a chain 24 or other flexible element being secured to the shaft 21 to be wound thereon. The lower end of the chain 24 is connected by a clevis 25 or otherwise to the free end of the lever. The outer end of

the shaft 21 has a head 26 through which a radial crank arm 27 is slideable, said arm being held in any adjusted position by means of a set screw 28 carried by the head 26. 5 The arm 27 has a crank handle 29 whereby the shaft or drum 21 can be readily rotated by hand. A ratchet wheel 30 secured upon the shaft 21 adjacent to the head 26 is adapted to be engaged by a pawl 31 carried by the 10 bearing 23 to prevent the chain 24 from unwinding when it has been wound upon the shaft to raise the lever 17, although the pawl can be disengaged from the ratchet wheel to permit the chain to unwind when it is desired to lower the lever 17.

Each bar or section 18 of the lever 17 carries suitable means for engaging the axle or other part of the vehicle. Thus, a standard 32 is provided for each bar 18, the same embodying bars 33 secured together adjacent to their upper ends, their lower terminals being separated, as at 34, to straddle the bar 18. The upper ends of the bars 33 have an axle seat 35 extending at an angle therefrom, and 25 the terminals or limbs 34 are secured pivotally to the bar 18 by means of a pin 36 engaged therethrough. A guide 37 is fastened by a bolt 38 or otherwise to the corresponding bar 2 of the base frame for the 30 terminals 34 to slide through when the axle or other part of the vehicle is seated on the seat 35. The bars 2 and 18 have series of apertures 39 for the engagement of the pin 36 and bolt 38, whereby the parts can be 35 adjusted.

A shorter standard or member 40 also straddles each bar 18, and is held in various adjusted positions by means of a pin or retaining element 41 engageable through the aperture 39. A longitudinal member 42 secured within the standard 40 slides and seats upon the bar 18, and the upper end of the standard 40 has a seat 43. Either of the two pairs of standards can be used, it being noted 45 that when the standards 32 are not in use, they can be swung out of the way, the terminals 34 being withdrawn from the stops 37.

In use, it will be noted that the jack can be readily slid under either end of an automobile to bring the fulcrumed end of the lever 18 underneath the machine, so that the axle seats are brought underneath the respective axle, and it will be noted that the jack can be moved underneath the bumper or tank 55 without inconvenience. Then, by rotating the crank arm 27 to wind the chain 24 upon the shaft or drum 21, this will raise the lever 17 and the axle or other part of the vehicle being engaged by the seats of the lever 17 60 will be raised. It will be noted that the lever has spaced seats for the axle, whereby to completely raise the corresponding end of the automobile, and a second jack can be

used for raising the other end of the vehicle, in which event, the vehicle can be pushed 65 about on the jacks.

In Fig. 5, a slight modification is illustrated, in that the lifting lever 17^a extends between the bars 2^a of the base frame, and only one of the bars 18^a of the lever is extended beyond the point where the bars 18^a converge together. A casting or cross piece 6^a between the bars 2^a has the casters 16^a applied thereto. In this form, the lever will be between the posts 4 of the base frame instead of at the outer side thereof as above described.

Fig. 7 illustrates a standard similar to that shown in Fig. 6, with the exception that one of the bars 33^a is shorter than the other. 80

A "single" jack is depicted in Fig. 8, whereas the jack shown in Figs. 1 and 2 is of the double type. The base or frame 1^b comprises the longitudinal side bars 2^b having the upturned portions 3^b at one end and 85 the upturned portions or posts 4^b at the other end provided with the brackets 5^b carrying the bearings 22 and 23 the same as the brackets 5 above described. Suitable supporting wheels 16^b are applied to the bars 2^b adjacent 90 to the ends thereof. The lever 17^b which projects at its free end between the posts 4^b for the connection of the chain 24 has its other end pivoted or fulcrumed between the portions 3^b, and this lever 17^b carries the 95 axle supports, the same as each of the bars 18 above described. If desired, as shown in Fig. 9, two or more fulcrum pins 20^b can be carried by the portions 3^b, and the lever 17^b has a notch 19^b for engaging the pins 20^b, in 100 order that the lever 17^b can be adjusted vertically.

Having thus described the invention, what is claimed as new is:—

A jack embodying a base having a pair of 105 bars provided with upturned posts at one end, said posts having brackets projecting away from the opposite end of the base, a lever fulcrumed upon the base near the last mentioned end thereof and projecting past 110 said posts under the brackets, bearings secured to and extending across the space between the brackets, a drum journaled in the bearings between the brackets, actuating means connected to the drum, and a flexible 115 element connected to the lever below the brackets and to the drum between the bearings to be wound thereon.

In testimony that I claim the foregoing as my own, I have hereto affixed my signature 120 in the presence of two witnesses.

JOHN M. LOWE.
